Primary Examiner — Jasmine Mlinarcik*Assistant Examiner* — James P McKane(74) Attorney, Agent, or Firm — Morgan, Lewis & Bockius LLP(57) CLAIM

The ornamental design for a garment, as shown and described.

DESCRIPTION

FIG. 1 is a front left perspective view of a garment showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The short evenly spaced broken lines depict stitching which forms part of the claimed design. The dash-dot-dash broken lines depict portions of the garment that form no part of the claimed design. The dash-dot-dot broken lines are boundary lines that form no part of the claimed design.
